CLAIM

The ornamental design for a marine electronics display device, as shown and described.

DESCRIPTION

FIG. 1 is a front perspective view of a marine electronics display device in accordance with an embodiment of the present invention;

FIG. 2 is a rear perspective view of the marine electronics display device of FIG. 1;

FIG. 3 is a front view of the marine electronics display device of FIG. 1;

FIG. 4 is a rear view of the marine electronics display device of FIG. 1;

FIG. 5 is a right side view of the marine electronics display device of FIG. 1;

FIG. 6 is a left side view of the marine electronics display device of FIG. 1;

FIG. 7 is a bottom view of the marine electronics display device of FIG. 1; and,

FIG. 8 is a top view of the marine electronics display device of FIG. 1.

The broken lines immediately adjacent the shaded areas represent the bounds of the claimed design while all other broken lines are directed to environment and are for illustrative purposes only; the broken lines form no part of the claimed design.
